PICNIC TABLE

Arthur C. Holmdahl, Kellogg, Iowa, assignor to Midwest Metal Stamping Co., Kellogg, Iowa, a corporation of Iowa

Application November 5, 1956, Serial No. 43,661

Term of patent 14 years

(Cl. D33—14)

Fig. 1 is a perspective view of a picnic table showing my new design;

Fig. 2 is a top plan view thereof; and

Fig. 3 is a side elevational view thereof.

I claim:

The ornamental design for a picnic table, substantially as shown.
